MULTIPLE PRESSURE PUMP

Elbert Litton Bivans, Los Angeles, Paul K. Beemer, Inglewood, and Paul H. Montgomery, Los Angeles, Calif., assignors to Preco Incorporated, a corporation of California

Application May 4, 1943, Serial No. 485,578

2 Claims. (Cl. 103—37)

1

The present invention lies in the field of pumps and compressors, and it is particularly concerned with the provision of a pump or compressor adapted to be selectively operated to produce multiple pressures or to pump differing volumes of fluid. The particular embodiment which is hereinafter described in some detail has been designed with a view to specific use in connection with hydraulic presses, but it will be understood that the invention is not necessarily limited to such particular use, nor to operation upon liquids in distinction from other fluids. The specific illustrative embodiment will, however, be described as for use in connection with a hydraulic press, as typical but not limitative.

Hydraulic presses of various types and in various uses are commonly operated to move the plunger at relatively high velocity and with a low operating pressure until the plunger brings up against the work. After contacting the work, the plunger is then operated by a smaller volume of fluid at higher pressure. The present invention provides a simple form of pump mechanism which may be selectively and automatically operated to deliver either a large volume of fluid at relatively low pressure, or a small volume of fluid at relatively high pressure.

The general nature of the invention will be most readily understood after consideration of the typical embodiments described in the following specifications and illustrated in the accompanying drawings in which

Figs. 1 and 2 are vertical sections illustrating one form of pump embodying the invention, Fig. 1 illustrating operation for delivery of fluid at low pressure and Fig. 2 illustrating operation for delivery of fluid at high pressure.

Fig. 3 is a section illustrating the essential parts of a modified form of pump mechanism, illustrating its operation for delivery of fluid at low pressure,

Fig. 4 is a similar view illustrating the operation of the pump of Fig. 3 for delivery of fluid at high pressure, and

Figs. 5 and 6 are diagrammatic sections illustrating further modifications.

One of the characteristics of our pump resides in its use of two or more movable fluid displacement members of different effective areas, both acting upon the same pressure fluid. These displacement members may, within the scope of our invention, be of any suitable number, and of any suitable types, such as for instance pistons, diaphragms or bellows. In the following described illustrative embodiment, the displacement mem-

bers are shown as reciprocating plungers, and are shown as two in number.

The movable displacement members are operated by actuating mechanism in such a manner as to be selectively operated by that actuating mechanism under control of the back pressures which are exerted on the displacement members. In one form of the apparatus illustrated (Figs. 1 and 2) that selective operation is semi-automatic, while in other forms (Figs. 3 to 6) the selective operation is wholly automatic.

We have mentioned the fact that, within the scope of the invention, the fluid displacement members may be of any suitable known type. They may also have any suitable physical relation to each other so long as they both act upon, and are reacted upon by, the same pressure fluids. In our illustrative embodiments of the invention which utilize two displacement plungers, we prefer to adopt the simple arrangement of locating a diametrically smaller one of two displacement plungers within the larger one, in such a manner that the actuating mechanism, which is here connected to the smaller of the plungers, becomes the actuating mechanism for both the plungers when both are operating to produce a relatively low pressure, and becomes the actuating mechanism for the smaller plunger alone when it is operating to produce a relatively high pressure by reciprocation within a cylinder formed in the larger plunger.

Referring now more particularly to the form of pump shown in Figs. 1 and 2, the main pump cylinder 10 has a large plunger 11 which may preferably be provided with a light spring 13 for urging it to its outermost position against a stop shoulder 12. Plunger 11 is the low pressure plunger of relatively large area. The smaller high pressure plunger 14 operates in cylinder bore 15 in the larger low pressure plunger 11.

In the form of apparatus shown in Figs. 1 and 2 an inwardly opening check valve 16 allows inflow of liquid through port 16 into cylinder 10 below the plungers; and an outwardly opening check valve 18 allows outward flow of the pressure fluid from port 17, through output tube 19 to the press or other apparatus where the pressure is used. Figs. 1 and 2 indicate that the pump mechanism may be mounted in a fluid reservoir 20, from which fluid, such as oil, is taken directly into inlet valve 16. In such a design, the element shown at 21 may be the plunger cylinder of the hydraulic press to which the output tube 19 leads.

In the form of apparatus shown in Fig. 1, the

outer end of high pressure plunger 14 is connected by link 25 to an oscillatory arm 26 on an operating shaft 27, which shaft is here shown as being manually operated through an oscillatory handle 28. The smaller plunger is shown as having a shouldered head 29 at its upper end, this shouldered head seating on the upper end of larger plunger 11 when the two plungers are in the relation to each other which is shown in Fig. 1. As will be understood when the following described mode of operation is considered, the upper shouldered end of smaller plunger 14 may be considered as a part of the operating linkage or mechanism for the smaller plunger. Consequently it may either be said that, in the relative positions of the plungers shown in Fig. 1, the operating mechanism of the smaller plunger has operating engagement with the larger plunger, or that the smaller plunger itself has such engagement with the larger plunger.

In operating at low pressure the two plungers maintain the relative positions shown in Fig. 1. That figure shows the whole mechanism with the two plungers at the upper or beginning end of the low pressure stroke. Downward movement of operating handle 28 from the position shown in full lines moves both plungers to the lower ends of their strokes. The effective displacement area is the aggregate area of the two plungers. A comparatively large volume of fluid, at relatively low pressure, is thus forced out of the pump cylinder to the hydraulic press, and continued reciprocation of handle 28 between the positions shown in full and dotted lines in Fig. 1 will move the press plunger comparatively rapidly. As soon as the press plunger comes up against its work, greater pressure per unit area is necessary to move it. The greater reaction pressure against the large aggregate area of the two plungers is immediately felt by the operator, who then moves handle 28 up to a higher position, as shown in Fig. 2, lifting the small high pressure plunger 14 to the relative position shown in that figure. The larger plunger 11 being now supported by the higher fluid pressure which is necessary to move the press plunger, the operator now oscillates handle 28 and high pressure plunger 14 between such an upper position as shown in Fig. 2 and a lower position where head 29 comes against larger plunger 11. Continued reciprocation of the smaller high pressure plunger causes the pumping of a relatively small amount of pressure fluid at relatively higher pressure. The relations of volumes and pressures in the two selective operations of the pump will of course be determined by the relative areas and strokes of the two displacement plungers, and they may be designed to provide any relative pressures and volumes which are desired.

In another mode of operation the stroke of smaller plunger 14 may always start from the uppermost position shown in Fig. 2. The first part of the downward stroke will bring plunger 14 to the position shown in Fig. 1, and a small volume of fluid will have been displaced against whatever pressure exists at the time. If the fluid pressure is low enough that the force applied to handle 28 can move larger plunger 11 down, then the stroke may go on through the downward movement of the larger plunger. Whenever the pressure builds up to the point where the applied force will not move the larger plunger down below the position of Fig. 1, then the stroke of the smaller plunger is automatically stopped in the position of that figure. Manual operation in

5 the manner just described involves the application of a limited force to that plunger which is directly actuated; and the same operation may be obtained by mechanical application of a limited force, acting through the full stroke distance. Such an arrangement is illustrated diagrammatically in Fig. 5, where an oscillating arm 26a may be constantly power driven to oscillate between the two positions indicated. The stroke of the arm may be transmitted to plunger 14 through spring 30, and when the full stroke is transmitted without compressing the spring, both plungers are moved through their strokes as above explained. The strength of spring 30 is so chosen that when the back pressure on plunger 11 reaches a chosen value the spring will be compressed and plunger 11 remain in its upper position while plunger 14 reciprocates alone.

10 It will be understood that return spring 13 is merely a convenient means for moving larger plunger 11 on its return stroke. When the pump is operating upon substantially non-expansive liquids there is no expansive pressure in the pump cylinder which can act to return the larger plunger to the top of its stroke. If the pump be applied to expansive fluids, the return spring is not necessary; but when applied to non-expansive fluids the spring forms a simple substitute for a positive mechanical means of moving the larger displacement plunger on its return stroke.

15 Figs. 3 and 4 illustrate the essentials of another typical pump design which is adapted to be entirely automatic in its operation, controlled solely by the reaction pressures on the fluids 20 which are being pumped. In these figures the physical design is also somewhat different from that shown in Figs. 1 and 2. The cylinder body 35, containing cylinder 36, is closed at its lower end by a plug 37 which contains the valve controlled inlet port 38 and outlet port 39, in which 25 the check valves 40 and 41 are located.

30 The larger plunger 43 has shoulder 44 which brings up against a cylinder shoulder 45 to limit the upward or outward stroke of the plunger. The smaller plunger 46, reciprocating in cylinder bore 47 in the larger plunger, is supported by a spring 48 with reference to the larger plunger. That spring 48 may be placed in any suitable physical position relative to the two plungers (for 35 instance, in the design shown in Fig. 1 such a spring might be placed between head 29 on the smaller plunger and upper end of the larger plunger). But in Figs. 3 and 4 spring 48 is preferably shown as housed within larger plunger 43, with its lower end resting upon a suitable seat 40 ring 49 in the larger plunger, and with the foot of the smaller plunger 46 resting upon the upper end of the spring. Such an arrangement will cause the larger plunger to be pressed downwardly by a force equal to the strength of spring 48, whenever the smaller plunger is moved downwardly. And spring 48 is selected to be of such strength as to transmit to the larger plunger a downward force which is equal to the total low 45 pressure on the larger plunger, plus such incidental pressures as that which is exerted by the return spring 50, and also plus the pressure necessary to overcome the inertia forces of the parts of the system moved by spring 48. At low operating speeds this last item may be negligible; at high speeds it is taken into account.

50 Return spring 50 is here shown as conveniently bearing at its upper end against the same seat ring 49 which foots the spring 48. In effect however spring 50 exerts its upward pressure against

larger plunger 43 to move that plunger upwardly on its return stroke, because spring 48 is considerably stronger than spring 50.

The design shown in Figs. 3 and 4 may be operated manually by such an operating mechanism as shown in Figs. 1 and 2. Figs. 3 and 4 show an operating mechanism which may either be manually driven or power driven. As shown in those figures an eccentric ring 55 is provided on an operating shaft 56. The operating shaft 56 may either be oscillated or continuously rotated, manually or by power. The eccentric ring 55 may bear directly upon the upper end of small plunger 46.

Fig. 3 shows the relative positions of the parts at the upper end of each stroke. If the fluid pressure in cylinder 36 is below that for which spring 48 is selected, the two plungers will move down as a unit, to expel a full volume of fluid at relatively low pressure; and reciprocation of the two plungers will continue as long as the fluid pressure is below that which corresponds to the strength of spring 48. However, as soon as the fluid pressure for any reason rises above the specified pressure, then the fluid pressure will hold larger plunger 43 at the upper end of its stroke, while smaller plunger 46 moves downward to the relative position shown in Fig. 4, compressing spring 48. Continued operation will then reciprocate smaller plunger 46 between the relative positions shown in Figs. 4 and 3, with the effect of pumping out a relatively small volume of fluid at the desired relative high pressure. Operation in the high pressure range, continuously compressing and expanding spring 48 does not cause waste of power as the spring upon release returns substantially all its energy of compression to the system.

We have said that spring 50 may be inserted at any suitable place in the drive for the larger or secondary plunger; for instance, between that plunger and the driving elements of the smaller or primary plunger. Fig. 6 shows such an arrangement diagrammatically, where the spring 50a is inserted between plunger 11 and head 29a of plunger 14. This arrangement has been spoken of before as the equivalent of spring 48 of Figs. 3 and 4. In any of the arrangements which have been described, the secondarily driven displacement member (the larger plunger here) can be said to be driven from the drive of the primarily driven member (the smaller plunger here), although in some cases (e. g., Figs. 3 and 4) the drive is specifically through the primarily driven displacement member.

Some general remarks in final summary may be helpful to an understanding of the invention typified by the described embodiments. Broadly speaking, the two plungers may be regarded as two movable fluid displacement members, one primarily driven and the other secondarily driven from the primary displacement member or from its drive means. In the form of Figs. 1 and 2 the selective action which determines whether or not the secondary member is driven, or whether the primary member alone is driven, depends either upon volitional change of stroke of the primary driving means, or upon the fact that a limited force (for instance, manual) is applied to the primary drive and that the stroke of that drive and of the primary displacement member is automatically changed when the back pressure against the secondary member exceeds the applied force. In these forms of the pump the pressures per unit area which can be raised (assuming a limited

force to be applied) depend entirely on the displacement areas of the displacement members.

In the form illustrated in Fig. 5 the selective action is also automatic in the same manner as mentioned just above, the limitation of applied driving force in the primary drive being supplied by spring 30. The same observations apply to this form as to the limited-force mode of operation mentioned just above.

In the forms illustrated in Figs. 3, 4 and 6 the stroke of the primary drive and primary displacement member is not changed. The automatic selective action in these forms of the pump depends upon the fact that the drive of the secondary displacement member—from the primary unit—includes a limited force transmitting element (spring 50 or 50a). In these forms, the unit pressure which can be raised by the secondary displacement member is determined by the total displacement area and the strength of the force transmitting element, regardless of how much power or force may be initially applied to the drive. But the unit pressure which can be raised by the primary displacement member is limited only by the amount of force which is applied to it; the two pressures are not necessarily in a ratio determined by the areas of the displacement members.

The area ratios of the two displacement members need not be unequal, and the area of the primary member need not be smaller than that of the secondary; with any ratio the volumetric displacement of the two members together is of course greater than that of the primary alone, and only for volumetric ratios greater than two to one will the displacement area of the primary member be less than that of the secondary.

We use the terms primary and secondary, as applied to the displacement members, in the sense that the primary member is the one which is directly driven and the secondary is the one which is selectively driven with the primary.

We claim:

1. In pumps of the type which include primary and secondary reciprocable fluid displacement members each exposed to and acting upon the same pressure fluid between inlet and outlet valves and having inward fluid displacement strokes and outward fluid induction strokes, the primary member being reciprocable independently of the secondary; a selective operating system for the displacement members which includes, a fixed stop which forms a terminal limit to the outward stroke of the secondary member and defines a position from which that member starts its inward stroke, a spring acting on the secondary member tending to move it outward to a position against the limit stop, the secondary member being also held against the limit stop by the fluid pressure on that member, and driving mechanism for the two members including, means for reciprocating the primary member through either of two spatially separated reciprocative movements, and a shoulder associated with the primary reciprocating means and adapted to drivingly engage the secondary member on inward movement only of the primary member to positively drive the secondary member inwardly, the primary member being otherwise free of connection with the secondary member and adapted to be reciprocated independently thereof, and the secondary member being at all times free to move inwardly from its outer stopped position excepting only for the spring pressure and the fluid pressure on it.

2. A selective operating system as specified in claim 1, and in which the primary reciprocating means includes a yielding element adapted to yield under a predetermined pressure driving the primary member inwardly.
